James H. Conklin of New York N.Y.
Letters Patent No. 272. Dated March 12. 1850.

The Schedule referred to in these Letters Patent and making part of the same.

To all whom it may concern:

Be it known that I, James H. Conklin of the City, County & State of New York, have invented or produced a new and ornamental design for a cooking stove. — And I do hereby declare that the following is a full and exact description of the same, reference being had to the annexed drawings making part of this specification.

Drawing No. 1. represents the front of the stove. A A being the fire or draught doors. B being a panel projecting out to receive the brick upon the inside. — Drawing No. 2. represents the side of the stove. A being the oven door. B being a panel representing the wood door.

What I claim as original, and desire to secure by
